Application December 12, 1952, Serial No. 22,682

Term of patent 14 years

(Cl. D44—10)

To all whom it may concern:

Be it known that I, Christy M. Del Mas, a citizen of the United States of America, residing at city, county, and State of New York, have invented a new, original and ornamental Design for a Sandwich and Hors d'Oeuvre Tray, of which the following is a specification, reference being had to the accompanying drawing, forming part thereof:

The figure is a perspective view of a sandwich and hors d'oeuvre tray embodying my new design.

The bottom of the tray is a flat plain surface.

I claim:

The ornamental design for a sandwich and hors d'oeuvre tray, as shown and described.

CHRISTY M. DEL MAS.
